CLAIM

The ornamental design for a “can bottom”, as shown and described.

DESCRIPTION

This application is related to Design Application No. 2001-17141 filed in Japan on Jun. 12, 2001 (the entire content of which is expressly incorporated herein by reference).

FIG. 1 is a perspective view of a can bottom which embodies my new and original design therefor which is shown with respect to an exemplary structural environment of other can walls forming no part of my claimed design,

FIG. 2 is a top plan view of thereof;

FIG. 3 is a bottom plan view thereof;

FIGS. 4 and 5 are right and left side elevational views thereof, respectively; and,

FIGS. 6 and 7 are front and rear side elevational views thereof, respectively.

The dashed lines in the accompanying FIGURES represent structural environment therefor, and forms no part of my claimed design.
